DESIGN FOR A VACUUM CLEANER

Wilbur V. Paine, East Hartford, Conn., assignor to
The Spencer Turbine Company, Hartford,
Conn., a corporation of Connecticut

Application April 12, 1949, Serial No. 1,925

Term of patent 7 years

(CL. D9—2)

To all whom it may concern:

Be it known that I, Wilbur V. Paine, a citizen of the United States, residing at East Hartford, in the county of Hartford and State of Connecticut, have invented a new, original, and ornamental Design for a Vacuum Cleaner, of which the following is a specification, reference being had to the accompanying drawing, forming part thereof.

Fig. 1 is a perspective view of a vacuum cleaner showing my new design.

Fig. 2 is a side view thereof.

Fig. 3 is a front view thereof.

Fig. 4 is a top plan view thereof shown on a reduced scale.

I claim:

The ornamental design for a vacuum cleaner, substantially as shown.

WILBUR V. PAINÉ.
